UNITED STATES PATENT OFFICE.

ALBION D. T. LIBBY, OF ELYRIA, OHIO, ASSIGNEE, BY MESNE ASSIGNMENTS, TO THE GARFORD MANUFACTURING COMPANY, OF ELYRIA, OHIO, A CORPORATION OF OHIO.

COMPOSITE ELECTRIC SYSTEM.

1,163,762.

Specification of Letters Patent. Patented Dec. 14, 1915.

Application filed January 12, 1911. Serial No. 602,135.

To all whom it may concern:

Be it known that I, ALBION D. T. LIBBY, a citizen of the United States, residing at Elyria, county of Lorain, and State of Ohio, have invented certain new and useful Improvements in Composite Electric Systems; and I do hereby declare the following to be a full, clear, and exact description of the invention, such as will enable others skilled in the art to which it appertains to make and use the same.

My invention relates to composite systems in which I combine a telephone and police system. I have here used the expression, police system, because such systems are generally employed in connection with police work, though they may be used for any analogous purpose, such as street railway, watchmen and other service, the object of the system being to furnish a system for signal and communication between a main or central station and itinerant persons, who are apt to be at distances from the telephone and who are to be signaled thereto. It sometimes happens in this service that one line is extended over the beats of several patrolmen and that it is desired to call only one of them. In such case, I group the stations which are posted upon the individual beats and by operating my selective device, I pick out the desired group. I aim to produce a combined police and telephone selective system to meet the requirements of this special demand.

My invention will be best understood by reference to the following description when taken in connection with the accompanying illustration showing one specific embodiment thereof, while the scope of the invention will be more particularly pointed out in the appended claims.

Figure 1 is a diagram of one form in which I have shown my invention. Fig. 2 is a diagram of a modified form. Fig. 3 is a diagram of an alternative detail. Fig. 4 is a plan view of the impulse sending device, showing the contact closed.

Referring now to the drawings and first to Fig. 1, I have illustrated the apparatus according to the symbols which are employed in this art. The main or central station is shown at I. In the police system,

this would be the police headquarters and in a despatcher's system, the headquarters of the despatcher. The composite line extends by its sides 1 and 2 to a plurality of substations, two of which are shown at II and III. The apparatus employed at each substation is illustrated at the station III alone. This will suffice, as the apparatus is identical except for minute details which will be described.

Referring to the apparatus at the main station, the main station attendant's set is shown upon the left of the figure.

R is the receiver, T the transmitter and B a source of current.

K₂ is the listening key by which the operator's set is connected to the line.

S is the register controlling relay and W the register outfit.

I₁ is the line lamp which is employed to apprise the main station attendant of a call from a substation. S₃ is the line relay which controls this lamp; S₁ is a relay which controls the connection of selecting current to the line. L is a guard lamp for the circuit of this relay.

K and K₁ are keys which control the circuit of the relay S₁.

X is a source of current here shown as a direct current generator, whose connection to the line is controlled by the relay S₁.

S₂ is a relay which controls circuits through the source X.

The impulse sending device is shown at E, there being an impulse sending wheel, such as here shown, for each individual or each group of stations which is controlled by a selector or selectors of a particular character.

Y is an indicating device which acts as joint means for indicating the operative or inoperative condition of the selecting means, the response of the sub-station attendant or subscriber and the number of sub-stations sets which have been operated in response to the call.

S₄ is a selector controlling relay bridged in series with a condenser C₃ across the line limbs 1 and 2.

O is a selector, such for example, as the Gill selector. I have mentioned this one because it is possible to use it with my system,

though I contemplate the use of any selector suitable for my purposes. The selector is operated by an electromagnetic device M.

S₅ is a signal controlling relay which is 5 in a normally open bridge of the line. The bridge of this relay is under the control of the selector.

L₂ is a lamp signal at the substation controlled by the relay S₅.

10 The substation set which includes the receiver R₁ and the transmitter T₁ is shown connected in series with a non-inductive resistance V in a normally open bridge of the line.

15 N is an impulse sending device and U a special key.

The apparatus itself and the functions thereof will be best understood from a description of the operation of my system 20 which is as follows: First, suppose the patrolman or other itinerant attendant desires to send in the register signal, which in most systems of this character he is expected to do at certain intervals of time, this signal is recorded at the main station and is for the purpose of keeping a check upon the itinerant attendants. He pulls down the lever 3 which starts the device N operating, the contacts 4 engaging the spring 5 and sending impulses over the following circuit: G₄—contact 4 of N—5—6—2—7—8—9—10—11—12—relay S—battery B₂ to ground G. The relay S is energized pulling up its armature 13 and closing the switch 13—14. This completes a circuit through the registering device W as follows: G—B₂—13—14—15—W— to ground G₂₀. This circuit will be made and broken each time a contact 4 engages the spring 5. The signal sending devices N at the different sub-stations have different arrangements of contacts. When it is desired to send in a special signal, such for example, as when an itinerant attendant needs special assistance, the button 16 of the device U is pressed down to engage the contact 17 completing a circuit as previously described, except that the circuit now passes from ground G₃ through 17, 16 and 18. This causes the register W to inscribe a long 50 dash upon the tape.

Should the attendant at the sub-station desire to communicate over the line with the central station, he removes the receiver R₁ from the hook 19. This hook being spring 55 pressed upward, will rise and engage the contact 20 completing a circuit from 20 through R₁—V₁—21—22—23—24—25—26—S₃—B₃—27—28—29—30—12—11—10—9—8—7—2—T₁ to 19. The relay S₃ will be energized over this circuit drawing up its armature 31 and closing a switch 31—32 in the circuit of the lamp L₁. This lamp will be energized over the circuit B₃—31—32—33—L₁—B₃. It will be noted that the circuit of the relay S₃ is controlled at the con-

tacts 28—29 by the relay S so that it will not be possible for an attendant at the substation to operate both signaling devices at the same time. Otherwise, the main station attendant seeing the line lamp L₁ lighted 75 might operate the key K₂ and interrupt the circuit of the relay S. The lamp L₁ is mounted in a position adjacent to the main station attendant, who seeing the same lighted operates the key K₂ and causing the 75 springs 10 and 24 to engage contacts 34 and 35 respectively. This bridges the attendant's set upon the line, current being supplied to the talking circuit by the battery B through the retardation coils 36 and 37. The attendant removes her receiver R from the hook 38 which rises and engages the contact 39. Conversation is then carried on from R—35—24—23—1—sub-station set 2—10—34—T—38—39—back to R. When the conversation is completed the two attendants 85 hang up their receivers and the listening key K₂ is thrown back to normal.

When the central station attendant desires to communicate with a patrolman upon the 90 beat, and in order to so communicate with him, it is desirable to select a station or a group of stations, she first operates the key K completing a circuit through G₂₁—B₁—S₁—40—K to G₁. The key is a non-locking key and rises to normal position as soon as released, but not until the relay S₁ has locked itself upon the following circuit: G₂₁—B₁—S₁—41—42—K₁ to ground G₂. The relay S₁ pulls up the armatures 7, 21 100 and 41, disconnecting the key K₂ and the relays S and S₃ from the line and closing the switches 21—43 and 7—44. The attraction of the armature 41 closes the switch 41—42 in the locking circuit. The lamp L which is in multiple with this relay is lighted to indicate the energization of this relay and to guard the same. Having operated the key K, the main station attendant picks out the particular impulse sender E which corresponds to the desired station or group of stations, seizes the operating lever F₁, pulls it down flexing spiral spring 45 which returns the wheel, the teeth F engaging a projection 46 upon a flexible contact carrying member 47. 48 is a support which carries the spring 47 and a second contact carrying the spring 49. Each time one of the teeth F engages a projection 46, the spring 47 is elevated until the contact 49 carried thereby, engages the adjustable contact 50 carried in a frame piece 51. A circuit will be completed by this switch as follows: 50—52—53—44—7—54—S₄—C₃—1—21—43—X—55—56—47—49. Although as shown, the generator X is a direct current generator and a condenser is interposed in this circuit, the flow of current in the circuit to charge the condenser is sufficient to operate the relay S₄, which pulls up its armatures 57 130

and 58, closing a shunt 59 of the condenser so that the rest of the energizing current of this impulse passes directly through the relay S_4 .

- 5 The attraction of the armature 58 closes switch 58—60 in the selector circuit 61 so that the remainder of the impulses will pass through the electromagnetic device M which steps the selecting mechanism O one 70 step forward for each impulse. When the projection 46 passes off of the first tooth into the recess between the teeth, these circuits will be interrupted and the driving pawl 62 will be turned to normal by the spring 63.
- 10 15 The needle of the device Y will be moved each time an impulse of current flows showing the main station attendant that the system is operated. Impulses of this character and with this effect will continue to be sent until the device E is returned to normal. During the sending of the last impulse, a contact 64 carried by the device E passes under a contact 65 mounted on the spring 49' which closes the following circuit: 20 25 49'—66— S_2 —67—68—69—70— X —55—56—57'—64—65. The relay S_2 will be energized, pulling up the armatures 71—72 and closing switches 71—73 and 72—74. The closure of the switch 71—73 locks the 30 35 relay S_2 in circuit with the generator X through the following circuit: X —55—71—73— S_2 —67—68—69—70 back to X . The closing of the switch 72—74 connects the generator X permanently to the line through the following circuit: X —55—74—72— Y —53—44—7—2—80— S_5 —the now closed switch 81—82—1—21—43—back to X . When the impulse sender E had completed its function, the contact 77 of the selector O engaged the member 81 closing the switch 81—82. The contacts 77 are placed 40 45 at different positions for different characters of selectors O employed in the system, so that the switches of the desired substations alone will be closed. The circuit just described through relay S_5 will energize the same causing it to pull up its armature 83 and close the switch 83—84 in the circuit 85 of the lamp L_2 . A source of current (not 50 shown) is connected in this circuit.

The lamp will be lighted and will continue to burn until disconnected by one of the attendants. The generator X was coupled to line through the action of the impulse sending device before it ceased operation. This having been done, the current was connected to line when the switch 81—82 was closed without delay and without any special action on the part of the 55 60 main station attendant. The needle of the device Y will be moved and will stand relatively steady while the lamp L_2 is burning. As soon, however, as one of the itinerant attendants answers, removing his receiver 65 from the hook and closing the sub-station

bridge 86, which is of much lower resistance than the bridge of the relay S_5 , there will be a greater flow of current in this circuit which will shunt the relay S_5 and deenergize the same and which will throw the 70 needle of the device Y to a different position and this will indicate to the main station attendant the response of a person at the called station. If several men respond, then the needle will be moved still farther from 75 O indicating to the operator the number of substations sets which have been operated. As a substitute for the device Y , I show in Fig. 3, a lamp L_6 which is connected in parallel with a resistance 89 through a conductor 88. The greater the flow of current through this lamp, the more intense it will burn, the main station attendant being schooled to read the conditions by the intensity of the light from the lamp L_6 is apprised of the conditions named by this lamp. As soon as the main station attendant has learned of the response of one of the itinerant attendants, she throws her listening key K_2 which interrupts the circuit of the relay 80 85 S_5 at 68—69. The relay S_5 will let go its armature 83 which is spring pressed to interrupt the circuit of the lamp L_2 at 83—84. The main station attendant will also operate the key K_1 which interrupts the circuit of 90 95 the relay S_1 and connects her talking set through to the local station. Conversation is then carried on over the circuit previously described.

It will thus be seen that among other things which I accomplish, my selective device is operated to pick out a particular station or group of stations and then automatically cut on a source of current which will remain on the line operating the signal 100 controlling device.

Referring to the modified form shown in Fig. 2, parts of the apparatus similar to parts employed in Fig. 1 are given the same reference numerals as are employed in Fig. 110 115 1. K_5 is shown a locking key. I have omitted the relay S_4 and connected the selector directly in bridge of the line. In the system shown in Fig. 2, I signal over one side of the line and ground, consequently 120 there is no danger of the line relay being operated through the circuits of the numerous bridges constructed across the main lines for the selectors. When the substation attendants desire to call the main station attendant, the key 100 is depressed until the spring 101 engages the contact 102. The circuit will then be completed from G_1' —102—101—1'—105—106—107—108—relay 125 S —battery B_3 to ground G' . The relay S is energized, pulling up its armatures 119—110. The armature 110 closes the switch 110—111 completing a circuit through the lamp L which burns indicating the call to the main station attendant. The latter op 130

erates the listening key K_7 and interrupts the circuit of the relay S which is deenergized and the lamp L retired. The springs 112 and 113 engage the contacts 114—115 respectively, connecting the main station attendant's set in circuit with the sub-station set over a circuit so similar to that described in reference to Fig. 1 that it will not be described here. Conversation being terminated, the two attendants hang up their receivers, the key K_7 is restored to normal and the system likewise restored to normal. Should the main station attendant desire to converse with one of the itinerant attendants along the route of the line, the key K_6 is operated. This key locks down, closing a circuit through the relay S , as follows: From ground G' —battery B_1 — S_1 — K_6 —120—121—119— G' . The relay S_1 is energized pulling up the armatures 103—122 and 123. This cuts off the key K_7 from the line and connects the terminals of the generator X thereto. The impulse sender E is then operated completing at each engagement of a tooth with the projection 146, a circuit as follows: 150—152— Y —153—144—123—2'—154— M —1'—103—143— X —155—147 and 149. The selector O will be stepped up until the catch 177 closes the switch 182—181 completing the bridge 180 of the relay S_5 . As this is done, the contact 164 engages the contact 165 completing a circuit from X through 155—157—164—165—166—relay S_2 —167—122—190 back to X . The relay S_2 pulls up the armature 171 and 172 closing the switches 171—173 and 172—174. The relay S_2 is then locked through 172—174— S_2 —167. The closing of the switch 171—173 connects the source X to line through a circuit independent of the impulse sender, causes a continuous flow of current to hold up the relay S_5 . This circuit is traced as follows: X —155—173—171—191— Y —153—144—123—2'— S_5 —180—182—181—1'—103—143—back to X . As before, the relay S_5 pulls up the armature 183 closing the switch 183—184 and lighting the lamp L_2 . When the substation attendant responds, the button 100 is first depressed, which as before described, closes a circuit through the relay S at the main station. The relay S will attract the armature 119 interrupting the circuit of the relay S_1 at 119—121, this relay will be deenergized allowing its armatures to fall back disconnecting the source X from the line and connecting the line through to the listening key K_7 . The attendants may then communicate as previously described. The indicator Y performs the same functions as described in connection with Fig. 1.

While I have shown these particular forms of my invention, it will be obvious to those skilled in the art that numerous and extensive departures from the details of

these forms may be made without departing from the spirit of the invention, these forms being shown solely for the purpose of clearly illustrating one specific embodiment of such invention.

70

I claim:

1. In a system of the class described, the combination of a main station, a plurality of substations, a combined police and telephone line, including line conductors connecting said stations, selectors at the substations, impulse sending means at the main station for operating said selectors, a source of current, and means to lock said source to said line conductors, and means governed by the impulse sending mechanism for controlling said locking means whereby it is operated during the sending of the last impulse.

75

2. In a system of the class described, the combination of a main station, a plurality of substations, a combined police and telephone line, including line conductors connecting said stations, selectors at the substations, impulse sending means at the main station for operating said selectors, a source of current and means to lock said source to said line conductors, and means governed by the impulse sending mechanism for controlling said locking means whereby it is operated before the impulse sending device has ceased to operate.

80

3. In a system of the class described, the combination of a combined police and telephone line, a central station, a plurality of substations connected thereto, signals at the substations, selectors for said signals normally disconnected from the line, means under control of the central station attendant for connecting said selectors to the line and a substation circuit controlled by the subscriber at the substation adapted when closed to cause the disconnection of said selectors from the line.

85

4. In a system of the class described, the combination of a combined police and telephone line, a central station and a plurality of substations connected thereto, signals at the substations, selectors for said signals normally disconnected from the line, electromagnetic means at the substations under control of the central station attendant for connecting said selectors to the line and a substation circuit controlled by the subscriber adapted when closed to shunt said electromagnetic means and thereby disconnect said selectors from the line.

90

5. In a composite electric system, the combination of a central station, a composite police and telephone line connected thereto, a plurality of substations on said line, selectors at the substations normally disconnected from said line, and means to connect all said selectors to said line when desired, said means locking itself to hold said se-

125

130

- lectors upon said line and means at the central station to control said selectors to select the desired station.
6. In a composite electric system, the combination of a central station, a plurality of substations, a composite police and telephone line connecting said stations, a signal at each substation, a source of current for operating the same, selecting means for connecting said signals in circuit with said source, said selecting means being normally disconnected from said line, a relay controlling the circuit of the selecting means normally connected to said line, a condenser in the circuit of said relay and means for charging said condenser, said relay adapted to be operated by the current which charges said condenser. 70
7. In a composite electric system, the combination of a central station, a combined police and-telephone line connected thereto, a plurality of substations on said line, police signal sending means at the substations, police signal receiving means at the central station, said police signal sending and receiving means operating over one of the conductors of said line, signals at the substations, selectors therefor normally disconnected from said line, means to connect one of said selectors to said line when desired to operate the same, means to operate said selectors to select the desired signal, and means to operate the signal when selected. 80
8. In a system of the class described, the combination of a combined police and telephone line, a central station and a plurality of substations connected thereto, signals at the substations, selectors at the substations normally disconnected from the line and means to connect said selectors to the line, said selectors being automatically disconnected from said line when a called substation responds. 90
9. In a system of the class described, the combination of a combined police and telephone line, a central station connected thereto, a plurality of substations connected thereto, signals at the substations, selectors for said signals normally disconnected from the line, means to connect said selectors to the line, means to operate said selectors and means controlled by the substation for disconnecting said selectors from said line. 100
10. In a system of the class described, the combination of an electric line, a central station and a plurality of substations on said line, signals at said substations, means at said substations for controlling said signals, selectors for controlling said means, means to control said selectors and means under the control of the subscriber for disconnecting said selector controlling means from said selectors. 110
11. In a system of the class described, the combination of a central station, a plurality of substations, a combined police and tele- 120
- of substations, a combined police and telephone line including line conductors connecting the same, signals at the substations, selectors for selecting the same, means at the central station for controlling said selectors 70 and joint means for indicating the operation of said first named means and the response of the substation. 125
12. In a composite system, the combination of a central station, a telephone line 75 connected to the central station, a plurality of substations connected to the line, signals at the substations, selectors at the substations for selecting said signals, controlling means at the central station for controlling 80 said selectors, an indicating device for indicating the condition of the substation apparatus on the called line, and means to connect said indicating device, said selector controlling means and said substation apparatus together in a circuit. 85
13. In a system of the class described, the combination of a central station, a plurality of substations, a combined police and telephone line including line conductors connecting the same, means at the central station to signal a substation and an indicating device to indicate both the response of a called station and the number of called stations which have responded. 95
14. In a system of the class described, the combination of a central station, a plurality of substations, a combined police and telephone line including line conductors connecting said stations, police signal sending 100 means at the substations and police signal receiving means at the main station operating over one of said line conductors, selectors at said substations, electroresponsive devices controlled by said selectors, a source 105 of current for operating said electroresponsive devices, means for connecting said source in circuit with a selected device and means for controlling the operation of said selectors and said connecting means. 110
15. In a system of the class described, the combination of a central station, a plurality of substations, a combined police and telephone line including line conductors connecting said stations, police signal sending 115 means at the substations and police signal receiving means at the main station operating over one of said line conductors, selectors at said substations, electroresponsive devices controlled by said selectors, a source 120 of current for operating said selectors and said electroresponsive devices and means for connecting said source in circuit with said selectors and a selected one of said devices, said source being connected in circuit with 125 the selected device before said source is disconnected from said selectors. 130
16. In a system of the class described, the combination of a central station, a plurality of substations, a combined police and tele-

phone line including line conductors connecting the same, police signal sending and police receiving means operating over one of said line conductors, selectors at the substations, electroresponsive devices controlled by said selectors, a source of current at the main station, an impulse sender for connecting said source to said selectors and means for connecting said source in circuit with the selected electroresponsive device, said means being operative to effect such connection during the sending of the last impulse of current by the impulse sending device.

17. In a system of the class described, the combination of a combined police and telephone line, a central station and a plurality of substations connected thereto, signals at the substations, selectors for said signals normally disconnected from the line and means under control of the central station attendant for connecting said selectors to the line, said means being controlled by the

subscriber at the substation for controlling said connecting means to disconnect said selectors from said line.

18. In a combined police and telephone system, the combination of a main station, a plurality of substations, line conductors connecting said stations, signals at said stations, selectors at said substations for selecting said signals, said selectors being normally disconnected from said line conductors, relays for connecting said selectors to said line conductors, condensers in the circuits of said relays, means controlled by said relays for shunting said condensers and means controlled by the subscribers for causing the interruption of such shunts.

In testimony whereof, I affix my signature in the presence of two witnesses.
